CHAIR OR SIMILAR ARTICLE

David D. Granger, Rte. 2, Conover, N.C. 28613

Filed May 15, 1967, Ser. No. 7,103

Term of patent 14 years

(Cl. D15—1)

FIGURE 1 is a front perspective view of a chair or similar article showing my new design with portions thereof broken away to indicate indeterminate length;

I claim:

The ornamental design for a chair or similar article, as shown,
